ATTORNEY

UNITED STATES PATENT OFFICE.

JOHN HERZOG, OF SAGINAW, MICHIGAN.

CABINET FOR TALKING-MACHINES.

1,308,420.

Specification of Letters Patent.

Patented July 1, 1919.

Application filed February 12, 1918. Serial No. 216,760.

To all whom it may concern:

Be it known that I, JOHN HERZOG, a citizen of the United States, residing at Saginaw, in the county of Saginaw and State 5 of Michigan, have invented certain new and useful Improvements in Cabinets for Talking-Machines; and I do hereby declare the following to be a full, clear, and exact description of the invention, such as will enable others skilled in the art to which it 10 pertains to make and use the same.

This invention relates to cabinets and pertains more particularly to record cabinets for talking machines and the like. The improvement 15 consists in a novel means whereby the casing of a talking machine can be easily and quickly secured to the top of a record cabinet in such manner as to impart an artistic and pleasing appearance to the 20 combined casing and cabinet and to securely hold them together as an integral structure while permitting the casing of the talking machine to be easily and quickly removed from the cabinet when desired.

The objects of my invention are to produce a fastening device for the above purposes that will be simple in construction, 25 strong and durable and capable of being easily applied and removed without unfastening screws, or breaking any of the finished joints in the fastening frame.

With the above and certain other objects in view which will appear later in the specification, my invention consists in the devices 30 described and claimed and the equivalents thereof.

In the drawings Figure 1 is a perspective view of a record cabinet and the casing of a talking machine secured together by means 35 of my improved device.

Fig. 2 is a transverse section through the cleats forming one side of the fastening frame, the foot of the casing of the talking machine being indicated by dotted lines.

Fig. 3 is a fragmentary top plan view of the outer cleats shown in Fig. 2.

Fig. 4 is a diagrammatic view showing the manner in which the outer frame of the fastening device is put in place by being 50 passed down over the top of the casing of the talking machine.

Fig. 5 is a perspective view of the four cleats of the inner frame assembled.

As is clearly shown in the drawings, the device consists in the record cabinet 1, upon 55 the top of which rests the casing 2 of a talking machine.

The fastening device, which comprises the subject-matter of my present invention, consists in an inner frame formed of cleats 3, 60 each cleat being secured to the top of the record cabinet by means of screws 6, or otherwise.

Each of the cleats 3 is shaped on its inner face to receive the legs of the talking machine casing, and preferably the cleats are so formed that their inner edges will engage the rubber bumpers 8 on the feet of the talking machine casing.

Four of the cleats 3 may be mortised together to form a single frame, which is then secured to the top of the record cabinet 1, but I prefer to make the cleats 3 separate to reduce the liability of breakage in shipment and handling.

An outer frame 4, formed of four cleats secured together to make an integral structure without visible joints is mortised at its lower edges to receive and inclose the cleats 3 of the inner frame, as shown in Fig. 2. 80 It will be noted that the cleats of this outer frame have their upper edges 5 overhanging the lower part or feet of the talking machine casing, thereby forming an inclosure for the base of the machine and adapted to 85 engage with it to securely hold the talking machine casing in place on the record cabinet.

To releasably secure the outer frame cleats 4 to the inner frame cleats 3, I provide on two or more of said cleats spring pressed pins 7 adapted to releasably engage corresponding recesses in the opposite cleat so that the outer frame when lowered into place will releasably engage the inner frame 95 in such a manner that it can be easily removed from the frame by being lifted.

It will be noted that the joints at the corners of the inner frame are all concealed when the outer frame is in place and that 100 the outer frame, being finished in one piece, shows no joints or cracks. The outer frame

being integral and four-sided is strong and not easily broken in shipping. It will also be observed that when the inner frame is in place the talking machine casing is merely set on this frame without sliding and the outer frame 4 is then applied by merely lowering it down over the body of the talking machine and snapping it in place by means of the spring-pressed pins 7.

10 Having thus fully described my invention; what I claim and desire to secure by Letters Patent is:

15 1. A cabinet having a top adapted to support the casing of a talking machine, an inner frame formed of cleats fixed to said top, an outer frame comprising four integral cleats, the opening of said outer frame adapted to permit the body of said casing to pass vertically through said outer frame 20 when the outer frame is lowered into position, the cleats of said outer frame having their inner sides overhanging and forming an inclosure for the outwardly projecting base of said machine and adapted to engage

therewith, to secure said base and cabinet together, and means for removably securing said inner frame and said outer frame together.

2. A cabinet having a top adapted to support the casing of a talking machine, an inner frame formed of cleats fixed to said top, an outer frame comprising four integral cleats, the opening of said outer frame adapted to permit the body of said casing to pass vertically through said outer frame 35 when the outer frame is lowered into position, the cleats of said outer frame having their bottom edges mortised to receive the cleats of said inner frame, the upper edges of said outer frame cleats overhanging and forming an inclosure for the base of said machine and adapted to engage therewith to secure said base and cabinet together, and means for removably securing said inner frame and said outer frame to- 40 45

In testimony whereof, I affix my signature.
JOHN HERZOG.
